CLAIM

The ornamental design for a combined flashing light and traffic cone, as shown and described.

DESCRIPTION

FIG. 1 is a front perspective view of a combined flashing light and traffic cone showing my new design.

FIG. 2 is a front elevational view thereof.

FIG. 3 is a rear elevational view thereof.

FIG. 4 is a side elevational view thereof, the opposite side being a mirror image.

FIG. 5 is a top plan view thereof.

FIG.1

FIG.2

FIG.4

FIG.3

FIG.5

FIG.6
